UNITED STATES PATENT OFFICE.

EMIL SALTZKORN AND LUDWIG NICOLAI, OF DRESDEN, GERMANY.

DESIGN FOR A MAT.

SPECIFICATION forming part of Design No. 25,652, dated June 16, 1896.

Application filed April 25, 1896. Serial No. 589,125. Term of patent 7 years.

To all whom it may concern:

Be it known that we, EMIL SALTZKORN and LUDWIG NICOLAI, citizens of Germany, residing in the city of Dresden, Germany, have invented and produced a new and original Design for Coiled Mats, of which the following is a full, clear, and exact description.

The nature of our design is fully illustrated in the accompanying drawings, in which—

- 10 Figure 1 is a plan view of the coiled mat, and Fig. 2 is a side elevation of the same.
As clearly illustrated in Fig. 1, the line of coil *a* starts at a point near the center of the mat, as at *a'*, and travels spirally and continuously throughout the entire mat to the outer edge, where the end of the line of coil terminates, as at *b*. Between the coiled lines 15 small projections *s* radiate as from a common center extending from one line of coil to the outer line of coil immediately in front of it, leaving open spaces between these projections. The radially-disposed projections *s* are about equidistant, spirally considered; but radially considered the projections of the 20 adjacent coils do not form a continuous ra-
25

dial line. They are scattered, in appearance producing a mottled, garbled effect. The outer edge of the mat, and also the inner spiral lines, if desired, have upon the upper and lower edges a series of semicircular protrusions *d* immediately above the projections *s*, which projections on the outer edge of the mat protrude from the surface of the outer edge, horizontally considered, forming a roughened surface.

The center of the coiled mat is hollow, as illustrated in Fig. 1.

Having thus described our invention, what we claim, and desire to secure by Letters Patent, is—

The design for a mat as herein shown and described.

In witness whereof we have hereunto set our hands this 19th day of March, A. D. 1896.

EMIL SALTZKORN.
LUDWIG NICOLAI.
